UNITED STATES PATENT OFFICE.

OLIN J. GARLOCK, OF PALMYRA, NEW YORK, ASSIGNOR TO THE GARLOCK PACKING COMPANY, OF PALMYRA, NEW YORK.

ROD-PACKING.

SPECIFICATION forming part of Letters Patent No. 716,836, dated December 23, 1902.

Application filed April 25, 1902. Serial No. 104,669. (No model.)

To all whom it may concern:

Be it known that I, OLIN J. GARLOCK, of Palmyra, in the county of Wayne and State of New York, have invented a new and useful Improvement in Rod-Packings, which improvement is fully set forth in the following specification and shown in the accompanying drawings.

My invention is an improved form or kind 10 of rod-packing, consisting of fibrous material and metal combined and formed in a novel manner, the same being hereinafter fully described, and more particularly pointed out in the claims, reference being had to the accompanying drawings, forming part of this specification.

Figure 1 is a side elevation of the body of packing, parts being broken away. Fig. 2 is 20 a view of the same seen as indicated by arrow 2 in Fig. 1, parts broken away. Figs. 3 and 4 are transverse sections on the dotted lines 3 3 and 4 4, respectively, in Fig. 1. Fig. 5, drawn to an enlarged scale, is a transverse section of the metal core, taken on the dotted line 5 5 in Fig. 1. Fig. 6 is a ring of the packing ready to be placed in a stuffing-box around the rod.

A in the drawings is an elongated prismatic strip or body of the packing, consisting 30 of strands of fibrous packing material of common kind—as flax, hemp, or other material—compactly braided around a metal core-piece B, the body being substantially rectangular or square in cross-section, as shown in Figs. 3 and 4. The core B is made of an inelastic pliable metal, as lead, tubular in form and transversely corrugated or indented at b b on opposite sides to better hold the strands of the braid. The dents or corrugations on the 40 opposite sides of the tubular core are alternated, as shown, and the core is perforated, as shown at a, the holes being usually made in or at the bottoms of the dents and opening from without into the bore c thereof.

The strips or bodies of packing formed as 45 stated are cut transversely into short lengths or pieces usually by an inclined or slant cut and bent to form rings, as shown in Fig. 6, of internal diameters corresponding with the

sizes of the rods to be packed. These rings 50 are subsequently immersed or soaked in hot oil or grease or waterproof compound in the usual manner of treating rod-packing, which oil or compound fills the tubular cores and when the packing is in use gradually flows 55 outward through the perforations to be taken up or absorbed by the fibrous body to keep up its saturation as the oil disappears therefrom on account of the action of the rod.

What I claim as my invention, and desire 60 to secure by Letters Patent, is—

1. Rod-packing consisting of a ring having a tubular core of pliable metal, as lead, and a braid of fibrous packing material formed around the metal core, substantially square 65 in cross-section, the core being transversely alternately corrugated and perforated, substantially as and for the purpose set forth.

2. Rod-packing consisting of a ring formed with a tubular core of soft metal, and compact fibrous packing material surrounding the core, the latter being indented or corrugated, and perforated, substantially as shown and described.

3. Rod-packing consisting of a body having 75 a tubular core, and a braid of fibrous packing material formed around the core, the core being alternately transversely corrugated and perforated, and of material different from that of which the braid is made, the body being bent to form a ring, substantially as shown and set forth.

4. Rod-packing consisting of an elongated prismatic body of compact fiber bent to form a ring, said body having a hollow metallic 85 core indented at different sides the indentations at one side alternating with those at the other side, and holes in said core opening from without into the interior thereof, substantially as and for the purpose specified. 90

In witness whereof I have hereunto set my hand, this 22d day of April, 1902, in the presence of two subscribing witnesses.

OLIN J. GARLOCK.

Witnesses:

EUGENE E. SMITH,
HENRY W. GUTHRIE.
